CATHODE RAY OSCILLOSCOPE OR THE LIKE

Richard A. Johnson, 124 W. Washington St., and Douglas E. Scott, 1225 Idlewild Drive, both of Round Lake, Ill. 60073

Filed Jan. 16, 1975, Ser. No. 541,550

Term of patent 14 years

Int. Cl. D10—04

U.S. Cl. D10—76

FIG. 1 is a front, top and right side perspective view of a cathode ray oscilloscope or the like showing our new design;

FIG. 2 is a bottom, rear, and left side perspective view thereof;

FIG. 3 is a front elevational view thereof;

FIG. 4 is a rear elevational view thereof;

FIG. 5 is a top plan view thereof, the bottom being identical therewith; and

FIG. 6 is a right side elevational view thereof, the left side being identical therewith.

We claim:

The ornamental design for a cathode ray oscilloscope or the like, as shown.
